UNITED STATES PATENT OFFICE.

MACKINTOSH HUTCHINSON, OF TORONTO, ONTARIO, CANADA.

WOODWORKING-MACHINE.

1,369,744.

Specification of Letters Patent. Patented Feb. 22, 1921.

Application filed January 5, 1918. Serial No. 210,470.

To all whom it may concern:

Be it known that I, MACKINTOSH HUTCHINSON, a subject of the King of Great Britain, residing at Toronto, in the Province 5 of Ontario, Canada, have invented certain new and useful Improvements in Woodworking-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of 10 this specification.

This invention relates to improvements in sawing machines of the general type disclosed in my U. S. Letters Patent No. 1,014,708 wherein a motor driven saw is 20 supported by an upright post or standard in such manner that it can be adjusted forwardly and rearwardly and positioned in different vertical planes radiating from a common axis in order that the machine may 25 be applied to mitering, cross-cutting, dadoing and kindred operations.

The principle objects of the present invention are to enhance the rigidity, compactness and facility of adjustment and operation of a machine of the type referred to; and also to enable the use of the saw driving motor for the operation of some device collaterally useful in the particular work at hand, such for example as a jointer, 30 without the necessity of removing the motor from its support or disturbing its operative relation to the saw.

With the above objects in view the invention consists of certain features of structure 40 and combination, involving the elements for supporting the motor and the saw from the standard or pedestal, and which will be set forth in detail as the description proceeds.

An embodiment of the invention is disclosed in the accompanying drawings, wherein:

Figure 1 is a side perspective view of a sawing machine, in which the features of the invention are incorporated;

Fig. 2 is a front perspective view of the machine;

Fig. 3 is a side elevation on a somewhat larger scale;

Fig. 4 is a plan view;

Fig. 5 is a detail front elevation showing the adjusting mechanism for the work table;

Fig. 6 is a detail view, partly in section and partly in side elevation, showing the mounting of the pivotally adjusted support bracket for the motor and saw. 60

Similar characters of reference designate corresponding parts throughout the several views.

The support of all of the elements of the machine consists essentially of an upright 65 standard or pedestal 1 suitably stayed at its lower end relatively to the floor and for this purpose preferably provided with a supporting base 2 of sufficient width and extent to insure stability. 70

The stock upon which the saw operates is held on a table 4 whose elevation relative to the saw may be adjusted to regulate the depth of the cut. In the construction shown and preferred the standard 1 is provided 75 with a forwardly projecting bracket 5 terminating in a cross beam 6 (Fig. 5) which, at its ends, is formed with vertical sleeves 7; and the table 4 is secured to a pair of pillars 8 which are slidably mounted in the 80 respective sleeves 7 and are connected at their lower ends by a cross bar 9. The adjustment of the elevation of the table is effected by the rotation of a screw shaft 10 which is threaded through the bar 9 and has 85 a swivel mounting in a suitable bearing formed with or secured to the beam 6. The stem 10 is operated by a hand wheel 11, preferably through the agency of miter gears 12. 90

In certain operations it may be found desirable to vary the angle of the work relatively to the saw and for this purpose the table 4 is pivotally adjustable about a horizontal or transverse axis, being connected 95 by pivot pins 13 to the upper ends of the pillars 8. In order to secure the table in any position to which it may be adjusted about its pivotal center 13 it is provided with curved bars 14, concentric to said center and having slots 15. The bars 14 are engaged by clamp heads 16 which are formed with suitable hand grips and have shanks passing through the slots 15 and threaded in the pillars 8. When the clamp 100 heads 16 are "backed off" the table 4 may be freely adjusted into any desired position about its pivotal center; and when the adjustment has been made said heads are tightened against the bars 14 and are there- 105 by effective to hold the table against displacement. 110

- The table is also preferably adjustable, in a direction fore and aft of the machine and for such purpose said table is provided with runners 4^a which are slidably fitted to bars 14^a extending between and secured to the upper ends of each curved bar 14. The pivot stems 13 are fitted centrally in the bars 14^a and the runners 4^a have longitudinal slots 4^b through which the stems 13 project.
- 10 Said stems are provided with clamp heads 13^a which are formed with suitable hand grips and may be tightened against the runners 4^a to fix the table against sliding movement and in any desired position within its
- 15 range of fore and aft adjustment.

- For the support of the saw 17 and its transverse shaft 18, as also of the motor 19 for operating the saw, a pair of beams 20 is provided which in turn are supported by 20 the standard 1. The saw shaft 18 is journalled in bearings 21 having elements which are formed as parts of or secured to a cross head 22. The cross head 22 is formed with sockets 23 in which the front ends of the beams 20 are fitted; and said cross head and beams are held relatively rigid by set screws 24 threaded through said socket and engaging said beams. The cross head 22 is also provided with a handle 25 by which the saw 25 may be advanced or retracted relatively to the work.

- In order to vary the angle of the saw relatively to the work the beams 20 are supported by a pivotally mounted element and 35 in order that the saw may be projected or retracted relatively to the work the beams are slidable on their supporting element in the direction of their length and are disposed tangentially of the pivot of said element.

- The supporting element for the beams 20 consists of a horizontal bracket 26 provided with a front pair of guide sleeves 27 and a rear pair of guide sleeves 28. The beams 45 are slidably fitted in said sleeves which, in order to facilitate the sliding movement of the beams in either direction are provided with pulleys 29 on which the beams rest, said pulleys being preferably mounted with 50 roller bearings. The pulleys are journaled in the bracket at the base of the sleeves, as shown, and thus relieve the sleeves of some of the strain of the beams. The motor 19 is provided with a base 30 which has depending dowel pins 31 engaging in recesses formed in the beams; and the sleeves 27 and 28 are formed along their upper sides with slots 32 which extend from end to end of said sleeves and through which the pins 55 31 may move in connection with the sliding of the beams, said slots thus permitting the motor to be moved in either direction past the sleeves. When the saw is retracted its rearward movement is limited by the engagement of the cross head 22 or, more

strictly, of the sockets 23 of said cross head against the front sleeves 27. The sleeves 27 and 28 are somewhat widely spaced and therefore provide support for the beams at two distantly located points, the arrangement thus insuring stability. The relatively wide separation of the sleeves 27 and 28 is not permitted to interfere with the compactness of the machine since an amply sufficient range of projection of the saw is provided 75 for with beams of the usual length by the slotting of the sleeves 27 and 28 which enables the motor to be advanced into a position of immediate adjacency to the front of the machine.

80 The bracket 26 is formed at a suitable point, preferably between the front sleeves 27, with a vertical collar 33 which is rotatably fitted upon a pivot post 34. The post 34 constitutes the axis about which the 85 saw may be turned to vary its angle relatively to the work.

In the preferred construction the post 34 is carried by an upright from the outer end of a horizontal overhanging arm 38 90 which is rigidly mounted upon the upper end of the standard 1, the post 34 being located at one side of said standard.

The bracket 26 may be secured in any desired position as indicated by a scale 36 95 provided upon the arm 38 in concentric relation to the collar 33. There are certain prescribed positions in which the saw must be placed for certain operations of frequent recurrence; and in order that the bracket 26 10 may be quickly adjusted to any of these prescribed positions and positively secured therein, it is preferred to provide a latch pin 35 which is mounted in a lug 35^a projecting from the collar 33 and is engageable, 10 selectively, in recesses 35^b formed in the arm 38 along a circle concentric to the collar 33. For holding the bracket 26 in positions intermediate the prescribed ones, as determined by the location of the recesses 35^b, the 11 collar 33 is preferably provided with a set screw 37 which may be tightened against the post 34, thereby to frictionally bind said collar against said post.

The shaft of the motor 19 is provided 11 with a pulley 40 which is geared by a belt 41 to a pulley 42 on the saw shaft 18.

The construction above described is such that the motor may be readily employed for the operation of some device collaterally 12 useful in the particular work at hand. Thus, a jointer 43 of any suitable construction and illustrated merely conventionally in the drawings is shown as mounted upon a horizontal bracket 44 which is secured to 12^b the standard 1, said jointer being located at the side of said standard opposite the table 4 and having its operating shaft 45 provided with a pulley 46. When it is desired to operate the jointer the bracket 26 is 13^c

5 turned about its axis 34, the beams 20 swing-
ing with said bracket to a position wherein
the pulley 40 alines with the pulley 46 at
which time the belt 41 is disconnected from
the pulley 42 and engaged over the
pulley 46.

10 By providing the overhanging arm 38 for
the support of the bracket 26 an advantage
is secured in that, when said bracket is, for
some special work, *e. g.*, ripping, positioned
15 at a right angle to its normal position shown
in Fig. 2 greater space is allowed be-
tween the saw and the post, thereby en-
abling the saw to work on wider boards.

15 Having fully described my invention, I
claim:

1. In a machine of the type set forth, an
upright standard, a horizontal bracket sup-
20 ported at the upper end of said standard for
pivotal movement about a vertical axis and
relatively to the standard, said bracket hav-
ing front and rear pairs of sleeves, a pair of
25 beams fitted in said sleeves for sliding
movement in the direction of their length
and disposed tangentially of the pivot of
said bracket, a cross head fitted on the front
30 ends of said beams, a transverse saw carry-
ing shaft, bearings for said shaft associated
with said cross head, a motor supported
from the rear ends of said beams and gear-
ing between said motor and the saw carry-
ing shaft.

2. In a machine of the type set forth, an
upright standard, a horizontal bracket sup-
35 ported at the upper end of said standard for
pivotal movement about a vertical axis, said
bracket having front and rear pairs of sleeves, a pair of beams fitted in said
sleeves for sliding movement in the di-
40 rection of their length and disposed tan-
gentially of the pivot of said bracket, said
sleeves being provided with pulleys jour-
naled in the bracket at the base of the
45 sleeves and on which said beams rest, a
cross head fitted on the front ends of said
beams, a transverse saw carrying shaft, bear-
ings for said shaft associated with said
cross head, a motor supported from the rear
50 ends of said beams and gearing between
said motor and the saw carrying shaft.

3. In a machine of the type set forth, an
upright standard, a horizontal bracket sup-
55 ported at the upper end of said standard for
pivotal movement about a vertical axis, said

bracket having front and rear pairs of 55
sleeves, a pair of beams fitted in said sleeves
for sliding movement in the direction of
their length and disposed tangentially of
the pivot of said bracket, a cross head fitted
60 on the front ends of said beams, a trans-
verse saw carrying shaft, bearings for said
shaft associated with said cross head, a mo-
tor having its base provided with dowel
pins fitted in said beams, the sleeves of the
65 rear pair having slots through which said
dowel pins may move in connection with the
sliding movement of said beams and gear-
ing between said motor and the saw carry-
ing shaft.

4. In a machine of the type set forth, an 70
upright standard, a horizontal arm mounted
in overhanging relation upon the upper end
of said standard, a horizontal bracket pivot-
ally mounted upon the outer end of said
arm for movement about a vertical axis 75
parallel to said standard, said bracket having
front and rear sleeves, a pair of beams fitted
in said sleeves for sliding movement in the
direction of their length and disposed tan-
gentially of the pivot of said bracket, a 80
cross head fitted on the front ends of said
beams, a transverse saw carrying shaft,
bearings for said shaft associated with said
cross head, a motor supported from the rear
85 ends of said beams and gearing between
said motor and the saw carrying shaft.

5. In a machine of the type set forth, an
upright standard, a horizontal arm mounted
in overhanging relation upon the upper
90 end of said standard, a horizontal bracket
pivotally mounted upon said arm for move-
ment about a vertical axis parallel to said
standard, a transverse saw carrying shaft, a
support for said shaft slidably fitted to said
95 bracket for movement in the direction of its
length, and disposed tangentially of the
pivot of said bracket, said shaft being
mounted at the front end of said support, a
motor mounted at the rear end of said sup-
port and gearing between said motor and 100
said shaft.

In testimony whereof I affix my signature
in presence of two witnesses.

MACKINTOSH HUTCHINSON.
